[57] **ABSTRACT**

A condition sensing bulb portion interconnected to capillary tube means that provides fluid communication therethrough to the chamber of the bulb portion whereby the tube and the bulb portion define a juncture area therebetween. Insulating means is carried by the device for insulating the juncture area at the exterior thereof so that substantially no adverse wide temperature gradient can be created between the bulb portion and the juncture area when the bulb portion is subjected to relatively high temperatures provided by flames imposed on the bulb portion. Such insulating means can be a metal sleeve disposed about the juncture area to provide a dead airspace about the juncture area.

FLAME-SENSING BULB CONSTRUCTION

This invention relates to a condition responsive device as well as to a method for making such a condition responsive device or the like.

It is well known that condition responsive devices have been provided in the past which are responsive to the existence of a flame at a burner means, such devices each having a flame-sensing bulb portion disposed in the flame area and containing expandable and contractable means, such as a fluid, which is expanded in the bulb portion when flames exist at the burner, the expanding means being transmitted by a capillary tube or the like to a power element which has an expandable and contractable wall portion that operates valve means, electrical switches, etc.

It has been found according to the teachings of this invention that if in the case of such prior known condition responsive devices a wide temperature gradient is created between the bulb portion and the juncture area defined where the bulb portion is interconnected to the tube means interconnected thereto when the bulb portion is subjected to relatively high temperatures provided by the flames being imposed directly thereon, the juncture area readily deteriorates and fails and thereby provide a relatively short life for the condition responsive device.

Accordingly, it is a feature of this invention to provide means for preventing such adverse wide temperature gradient between the bulb portion and the juncture area.

In particular, one embodiment of this invention provides a cylindrical metal sleeve that has a first portion telescopically disposed about the bulb portion and a second portion extending from the bulb portion in telescoping spaced relation about the juncture area between the bulb portion and the tube means and along the tube means for a predetermined distance to provide a substantially dead airspace completely about the juncture area so as to prevent an adverse wide temperature gradient being created between the bulb portion and the juncture area so that the juncture area remains at substantially the same temperature as the bulb portion whether or not the bulb portion is being immersed in flames.

Accordingly, it is an object of this invention to provide an improved condition responsive device having one or more of the novel features set forth above or hereinafter shown or described.

Another object of this invention is to provide an improved method of making such a condition responsive device or the like, the method of this invention having one or more of the novel features set forth above or hereinafter shown or described.

Other objects, uses and advantages of this invention are apparent from a reading of this description which proceeds with reference to the accompanying drawings forming a part thereof and wherein:

FIG. 1 is a fragmentary side view, partially in cross section, illustrating a prior art flame-sensing means.

FIG. 2 is a view similar to FIG. 1 and illustrates the improved flame-sensing means of this invention.

While the various features of this invention are hereinafter described and illustrated as being particularly adapted to provide flame-sensing means for a pilot burner means or the like, it is to be understood that the various features of this invention can be utilized singly or in any combination thereof to provide condition responsive means for other arrangements as desired.

Therefore, this invention is not to be limited to only the embodiment illustrated in the drawings, because the drawings are merely utilized to illustrate one of the wide variety of uses of this invention.

Referring now to FIG. 1, a prior art condition responsive device is generally indicated by the reference numeral 10 and comprises a bracket means 11 carrying a pilot burner means 12 having an outlet means 13 for the issuing of fuel that is ignited in a conventional manner to produce flames 14 that are directed by a flame shield 15 of the pilot burner 12 about a flame-sensing bulb portion 16 having one end 17 thereof

received in an opening means 18 of the flame shield 15 and the other end 19 thereof interconnected to a capillary tube 20 in a conventional manner that defines a juncture area 21 therebetween. A relatively thick cylindrical sleeve 22 is telescoped about the tube 20 so as to carry the same and has one end 23 thereof abutting against the juncture area 21 between the tube 20 and bulb 16 whereby the sleeve 22 can be received in suitable opening means 24 in the bracket means 11 to support the other end 19 of the bulb 16 in a generally horizontal position so that the bulb 16 will be fully immersed in the flames 14 when such flames 14 are created at the outlet 13 of the pilot burner means 12.

The bracket means 11 also is utilized to mount the pilot burner means 12 and bulb arrangement 16 in a suitable position in the apparatus or device receiving the same.

It has been found that during the operation of the condition responsive device 10 of FIG. 1 over a relatively short period of time, such as three months, the condition responsive device 10 failed in the juncture area 21 between the bulb portion 16 and the tube means 20.

Accordingly, this invention solves such failure problem at the juncture 21 between the tube means 20 and bulb portion 16 of the device 10 of FIG. 1 as well as for similar devices.

In particular, it was found, according to the teachings of this invention, that a high temperature gradient was being created between the bulb portion 16 and the juncture area 21 between the bulb 16 and tube 20 because the flame 14 of the burner 12 surrounded the bulb portion 16 while the bracket means 11 at the opening means 24 thereof being disposed in intimate contact with the sleeve 22 and the cylindrical sleeve 22 being disposed in intimate contact with the tube 20 acted as a heat sink or a highly conductive path for directing the heat of the juncture area 21 therefrom so that the juncture area 21 was at a relatively low temperature while the bulb portion 16 was at a relatively high temperature. The wide temperature gradient is believed to be the cause of the failure problem in the juncture area 21 of the device 10.

Therefore, one of the features of this invention is to provide insulation means about the juncture area 21 so as to prevent an adverse temperature drop in the juncture area 21 when the bulb 16 is being heated by the flames 14 whereby no adverse wide temperature gradient can be created between the bulb portion 16 and the juncture area 21.

Accordingly, reference is now made to FIG. 2 wherein the condition responsive means of this invention is generally indicated by the reference numeral 30 and comprises the bracket means 11A, pilot burner means 12A and flame shield 15A of the prior art device 10. However, the bulb portion 31 of the condition responsive means 30 of this invention, while being shaped slightly differently at the free end 32 thereof than at the free end of the bulb 16 of FIG. 1, could be of the same configuration as the bulb portion 16 if desired. The bulb 31 is interconnected by a juncture area 33 to the capillary tube 34 that leads to the control device 35 which, in the embodiment of FIG. 2, comprises an electrical switch means 36 operated by the movable wall means 37 of expandable and contractable power element 38 in a manner conventional in the art. While the bulb portion 31 and tube 34 are integral so that the juncture area 33 is integral therewith as will be apparent hereinafter, it is to be understood that the tube 34 and bulb 31 could be separate parts subsequently secured together to define the juncture area 33.

In order to insulate the juncture area 33 from the surrounding atmosphere and from the bracket means 11A, a cylindrical metallic sleeve 39 is provided and has a first portion 40 fully receiving the bulb portion 31 therein and a second portion 41 extending from the end 42 of the bulb portion 31 to the left in FIG. 2 a sufficient distance to carry the same well beyond the juncture area 33 whereby a substantially dead airspace 43 is provided in the sleeve 39 to completely surround the juncture area 33 as well as a portion of the tube means 34 leading from the juncture area 33 so as to prevent a high temperature gradient between the bulb portion 31 and the juncture area 33 when the burner means 12A is creating the flame means 14A.

The sleeve 39 has opposed open ends 44 and 45, the open end 45 extending beyond the free end 32 of the bulb portion 31 and being suitably necked inwardly at 46 adjacent the end 32 of the bulb 31 and necked inwardly by a plurality of dimples 47 adjacent the other end 42 of the bulb portion 31 so as to maintain the sleeve 39 in assembled relation on the bulb portion 31 in the configuration illustrated in FIG. 2.

Thus, it can be seen that the necked portion 45 of the sleeve 39 can be received in the opening means 18A of the flame shield 15A to support the forward end thereof and the second portion 41 of the sleeve 39 can be received in the opening means 24A of the bracket means 11 to support the other end thereof whereby the sleeve 39 can be utilized in conventional bracket means to provide the unique function previously described.

The above inward necking 47 and 46 of the sleeve 39 is accomplished in a manner to prevent the deforming of the bulb portion 31 while still limiting play between the sleeve 39 and the bulb portion 31 to a tolerable degree.

While the sleeve 39 could be formed of any suitable material to provide the aforementioned function, it has been found that when the bulb 31 and capillary tube 34 are formed from metallic tubing material AFTM-446 having an original diameter of the desired bulb size 31 so that the same can be subsequently swaged down to form the capillary portion 20 in a conventional manner whereby the capillary portion 34 and bulb portion 31 are integral at the juncture area 33, the sleeve 39 for such a formed bulb 31 can comprise Incoloy tubing of the International Nickel Company having a composition of approximately 30 to 35 percent nickel; 19 to 23 percent chromium; a maximum 0.1 percent carbon; a maximum of 1½ percent manganese; a maximum of 0.03 percent sulphur; a maximum of 1 percent silicon; and a maximum of 0.75 percent copper with the remainder being iron.

Such a sleeve 39 has an inside diameter of approximately 0.130 inch and a wall thickness of approximately 0.020 inch. Such a tube is approximately 1.750 inches in length for a bulb length of approximately 0.800 inch.

In view of the above, it can be seen that this invention not only provides an improved condition responsive means for a pilot burner or the like, but also this invention provides an improved method of making such a condition responsive means or the like.

While the form of the invention now preferred has been disclosed, as required by statute, other forms may be used, all coming within the scope of the claimed subject matter which follows.

What is claimed is:

1. In combination, a burner, a controlled device to be responsive to flames at said burner, bracket means carrying said burner, a flame-sensing bulb portion carried by said

- bracket means and having an exterior wall means defining chamber means in said bulb portion, said bulb portion being located by said bracket means in the flame area of said burner, tube means interconnected to said bulb portion and providing fluid communication therethrough from said chamber to said controlled device whereby said tube means and said bulb portion define a juncture area therebetween, said bulb having a relatively large transverse cross-sectional dimension in relation to the relatively small transverse cross-sectional dimension of said tube means at said juncture area whereby said tube means has a tendency to fail and break off at said juncture area when a relatively wide temperature gradient is repetitively created between said bulb portion and said tube means at said juncture area, and means insulating said juncture area at the exterior thereof from the atmosphere and from said bracket means so that substantially no adverse wide temperature gradient is created between said bulb portion and said juncture area when said bulb portion is subjected to relatively high temperatures provided by said flame means issuing from said burner and surrounding said bulb portion.
2. A combination as set forth in claim 1 wherein said last-named means also insulates said tube means from said juncture area to a point spaced from said bulb portion.
3. A combination as set forth in claim 1 wherein said last-named means insulates said juncture area by providing a substantially dead airspace about the same.
4. A combination as set forth in claim 1 wherein said last-named means comprises a sleeve disposed about said juncture area to provide a substantially dead airspace about the same.
5. A combination as set forth in claim 4 wherein said sleeve has a first portion receiving said bulb portion therein and a second portion extending from said bulb portion in telescoping spaced relation about said tube means, said sleeve being carried by said bracket means whereby said bulb portion is carried by said bracket means.
6. A combination as set forth in claim 5 wherein said sleeve has opposed open ends respectively at said first and second portions thereof, the open end at said first portion extending beyond said bulb portion in a direction away from said juncture area and the open end at said second portion extending along said tube means away from said juncture area in the opposite direction.
7. A combination as set forth in claim 6 wherein said bulb portion has opposed ends and wherein said first portion of said sleeve is necked inwardly adjacent said bulb portion at said opposed ends thereof to hold said sleeve on said bulb portion.
8. A combination as set forth in claim 7 wherein one of said ends of said bulb portion is a closed end and the other end of said bulb portion is necked inwardly to said tube means and defines said juncture area therewith.
